BED ATTACHMENT FOR INVALIDS

Harry Y. Armstrong, Syracuse, N. Y.

Application November 16, 1934, Serial No. 753,363

3 Claims. (Cl. 5—317)

This invention relates to bed attachments, more particularly to an attachment for a bed by which an invalid, or patient, may assist himself in movement about the bed.

- 5 An object of the invention is a device of the type referred to which may be readily and conveniently attached to, or removed from, the bed without the employment of any tools, or other equipment.
- 10 A further object of the invention is a bed attachment for invalids, and the like, which normally may be maintained in a position where it is entirely out of the way, and may be conveniently and quickly swung into operated position.

15 A further object of the invention is a device of the type referred to which is economical in manufacture, employing a minimum number of parts, and at the same time highly efficient and durable in use.

20 A further object of the invention is a bed attachment provided with a hand grip by which the patient may move himself about in the bed, and which hand grip is adjustable to suit the needs and conditions of any patient.

25 The invention consists in the novel features, and in the combinations and constructions hereinafter set forth and claimed.

30 In describing this invention, reference is had to the accompanying drawing in which like characters designate corresponding parts in all the views.

35 Figure 1 is a side elevation, partly in section, showing the device attached to a bed.

Figure 2 is a view taken on lines 2—2, Figure 1.

40 Figure 3 is a view, in elevation, of the hand grip.

The invention consists generally in a vertical support provided with an overhanging arm, a hook structure engaging the upper horizontal rail of the bed, and a second hook structure engaging the lower horizontal rail, the support being provided with suitable means for adjusting the hook structures to clamp the device to the bed, and a hand grip depending from the overhanging portion of the support, and means for adjusting the grip toward and from the patient.

45 10 indicates generally the bed which, as here shown, is provided with the usual head posts 11, and foot posts 12. The posts 11 and 12 may be U shaped in general formation, with the connecting portion of the U forming the upper horizontal rails 13, 14, or the rails 13, 14, may be welded, or otherwise secured, to the foot posts. As here 50 shown, the bed is provided with the usual lower

horizontal rails 15, 16, and vertical bars 17, 18, connecting the cross rails 13, 15; 14, 16.

5 Bed attachments for invalids have been constructed heretofore, but I have found that such devices are comparatively intricate and complicated, with the result that their cost is prohibitive for general adaptation, and in addition they are so constructed that they can not be readily and conveniently attached to and removed from beds. My device, as will more fully appear as the 10 specification proceeds, can be readily and conveniently attached to the bed without the use of any tools, or special equipment. This feature is extremely important in the case of hospitals where such attachments are usually manipulated 15 by the nurses who have neither the time, nor equipment, to operate intricate and complicated devices.

20 My bed attachment consists of a vertical support 20 formed, or provided, with an angular extension or arm 21. As here shown, the support 20 is of tubular formation, and the arm 21 integral therewith. An abutment, or collar 22 is welded, or otherwise secured, to the support 20, and the lower end of the support is threaded a 25 considerable distance, as at 23.

25 The support is detachably secured to the bed, by means of a pair of hook structures designated generally 24, 25. The hook structure 24, as indicated in Figure 1 of the drawing, consists of a sleeve 26 provided with a bore to slidably receive the support 20. A hook 27 is secured to the sleeve 26, as by welding, or the sleeve 26 and hook 27 may be formed integral.

30 Referring to Figure 2, the hook 27 is of U shaped formation with the loop 28 of the hook passing about the sleeve 26, and the legs 29, 30, providing a pair of spaced apart hooks which engage or hook over the upper horizontal cross rail 13 of the bed.

35 The lower hook structure 25 is of the same construction as the upper hook structure, and consists of a sleeve 31 and U shaped hook 32. Usually, the upper rail 13 is of greater diameter than the lower rail 15. However, on account of the 40 formation of the hooks 27, 32, a large variation in rail sizes is taken care of. The hooks 27, 32, are provided with suitable covering 33 to prevent marring of the rails 13, 15.

45 Preferably, an antifriction thrust bearing is interposed between the collar 22 and the sleeve 26 of the hook structure 24. As here shown, a pair of hand nuts 34 are threaded upon the lower end 50 55 55 of the support 20, an antifriction thrust bear-

ing 35 being interposed between the lower hook structure 25 and the upper hand nut 34.

The device is attached to the bed by hooking the upper hook structure 24 over the upper horizontal rail 13. The hand nuts 34 are then adjusted sliding the lower hook structure 25 upwardly until the hooks 32 engage the lower rail 15. The hand wheels are adjusted with a light pressure against the lower hook structure 25, and 10 are then locked in this adjusted position. It will be observed that the device is attached to the bed in a most convenient manner, and with the minimum consumption of time, and once the device is attached to the bed, there is no danger 15 whatever of it becoming loosened, or otherwise coming off from the bed. It will be observed that the support 20 is thus journaled in the hook structures 24, 25, and relative rotatable movement of the support is permitted. This feature 20 permits the device to be used to assist patients, or invalids, in getting in and out of the bed.

When the device is not in use, the arm 21 may be swung parallel with the rails 13, 14. The bed attachment is provided with a suitable hand grip 25, 40, as shown in Figures 1 and 3. As here shown, the hand grip 40 is of substantially triangular formation, the base of the triangle comprising a cylindrical hand grip 41, and the apex 42 of the triangle being secured to the end of a flexible 30 chain or cable 43. The cable 43 extends into the tubular support 20, and at its inner end is provided with a suitable weight 44 which is free to travel within the support 20. In order that the hand grip 40 may be adjusted to suit the individual 35 requirements of the patient, I provide means for varying the length of the chain, or cable, extending from the end of the arm 21. The arm 21 is provided with a pin 45 which extends through the arm, and engages one of the 40 links of the chain, as shown in Figure 1. To adjust the hand grip 40, it is only necessary to remove the pin 45, pull the cable or chain 43 out of the arm, and reinsert the pin. Or, if it is desired to adjust the grip 40 to a higher position, 45 after removal of the pin 45, the cable is drawn in the support by the weight 44 when the hand grip 40 is lifted. Obviously, any suitable means may be employed, other than the pin 45, to adjust the cable 43. To prevent the pin 45 from 50 being lost, it is flexibly secured to the arm 21 by chain 46.

I have found in practice that the flexible support in the nature of a chain, or cable, is highly desirable for the hand grip. This permits the 55 grip to be twisted, or turned, according to the movements of the patient.

When the support 20 is rotated so that the arm 21 extends over, or overhangs, the bed, as shown in Figure 1, it is desirable to maintain the device in this position while it is in use. To effect this result, without the use of intricate mechanism, I have provided a simple latch arrangement which is quickly and conveniently operated and which maintains the device in operated position.

Referring to Figure 2 of the drawing, a latch or retainer 47 is pivotally mounted upon the collar 22. The latch 47 is Y shaped in general formation, the legs of the Y being provided with 70 pins or trunnions 48, the inner ends of which are journaled in apertures in the collar. The

leg portion of the Y formation, or the outer end of the latch 47, is of such width as to drop between the legs 29, 30, of the hook structure 24, and rests upon the upper surface of the upper rail 13, as shown in Figure 1. When in this position, the support is held from rotatable movement. When it is desired to swing the arm 21 parallel with the end of the bed, it is only necessary to raise the flap or latch 47, and swing the support.

It will be observed that I have devised a bed attachment of the type described, which is economical in manufacture, and while light in weight and easily manipulated, is sufficiently strong and durable to meet all requirements.

The method of securing the attachment to the bed is simple in construction and easily operable, it being only necessary to hook the upper hook structure 24 over the upper bed rail. With the device thus suspended, the hand wheels 34 may 20 be easily adjusted. The structure of the device is such that its attachment and all adjustments can be readily and quickly made by nurses, or attendants in hospitals.

What I claim is:

1. In a bed attachment for invalids including a vertical support provided with an arm overhanging the bed, an abutment secured to the support, a hook structure mounted upon the support and having relative rotatable movement thereto, the hook structure engaging the upper horizontal rail of the bed and abutting against the abutment on the support a second hook structure slidably mounted upon the support and engaging the lower horizontal rail of the bed, 35 means carried by the support and operable to adjust the second hook structure toward and from the first hook structure to clamp the device to the bed, a hand grip depending from the overhanging arm of the support, and means for adjusting said hand grip toward and from the bed.

2. A bed attachment for invalids including a one-piece tubular support having a portion overhanging the bed, a hand grip depending from the overhanging portion of the support and being adjustable toward and from the bed, a pair of hook structures engaging the horizontal rails of the bed and detachably securing the attachment to the bed, and means carried by the support and operable to engage one of said hook structures to prevent swinging movement of the overhanging portion of the support.

3. A bed attachment for invalids including a pair of hook structures for engaging the horizontal rails of the bed, a one-piece tubular support formed with a horizontal extension, said support being journaled in said hook structures and being provided with a fixed abutment engaging one of said hook structures, and an adjustable abutment engaging the other of said hook structures, means carried by the fixed abutment on the support and engaging the adjacent hook structure to prevent rotatable movement of the support relative to the hook structures and the bed when the angular portion is overhanging the bed, a flexible cable arranged in the tubular support and extending outwardly from the end of the angular arm, and means for adjusting said cable.
